UNITED STATES PATENT OFFICE.

JOSEPH D. LACROIX, OF NEW ORLEANS, LOUISIANA, ASSIGNOR TO EUGENE H. DAVIS,
OF NEW YORK, N. Y.

CIGAR-MAKING MACHINE.

1,088,827.

Specification of Letters Patent.

Patented Mar. 3, 1914.

Application filed August 16, 1904. Serial No. 220,920.

To all whom it may concern:

Be it known that I, JOSEPH D. LACROIX, a citizen of the United States, residing at New Orleans, in the parish of Orleans and 5 State of Louisiana, have invented new and useful Improvements in Cigar-Making Machines, of which the following is a specification.

This invention relates to cigar making machines, and the primary object of the same is, by means of comparatively simple mechanism, to facilitate the operation of applying wrappers to cigars, binder to a filler to make a bunch, or a wrapper to a 10 bunch, or both, either manually or by mechanism, to increase the output of the completed product within a given time. Furthermore, to have the organization of contributing elements so arranged that a part 15 or all of the same may be utilized in manufacturing cigars and permit the formation of a product either wholly by mechanism or partly by mechanism and by hand. Furthermore, to dispense with intricate mechanism, where the bunches are made mechanically, for transferring the same either to mechanically operated wrapper-applying mechanisms, or to a point where the bunch may be deposited and have the wrapper 20 manually applied thereto; furthermore, to effect feeding the wrapper to a bunch in the wrapper-applying mechanism in such manner as to cause it to conform exactly to the shape of the bunch, and also to effect 25 proper finishing of the tip of the cigar; finally, generally to improve the details of construction of a cigar machine, capable of making a bunch, transferring the same to wrapper-applying mechanism, applying the 30 wrapper and regularly discharging the product, when completed, and reduce the mechanism for the several steps and minimize and individually simplify their construction.

45 It is well known in the art of cigar making that the compression of the bunch previous to application of the outer leaf or wrapper is dependent on the nature of the raw material used and also on atmospheric conditions existing at the time. The extent of 50 rolling and compressing a bunch must be governed to compensate for the surrounding conditions just mentioned at the time of preparation or formation of the bunch.

55 For instance, if the tobacco contains too

much moisture or is too dry, less compression is given. Dry tobacco will not stand much compression, as an excessive pressure will cause the same to crumble. Moist tobacco, if not carefully handled in making 60 bunches, will become too compact and prevent a free draft through the finished cigar, even after the latter is thoroughly dry.

The mechanism embodied in the present machine has been devised to cause the bunch 65 to be compressed just to the proper degree and the wrapper to be applied evenly and smoothly thereto without danger of tearing, creasing, or dragging, irrespective of the atmospheric conditions or the nature of the 70 tobacco or components of the cigar at the time the bunch is being made and the wrapper applied.

The machine embodying the features of the invention is capable of compressing, 75 shaping, transferring, and depositing a bunch either to a hand operator, or to wrapper-applying mechanism. It is also adapted to receive a completed bunch made either by hand or by other mechanism and to compress and shape the same, and further is arranged to coact with a belt initially supporting the filler and binder, and wrapping the binder around the filler, thereby making 80 the completed bunch.

If preferred, supplemental bunch making mechanism may be employed in conjunction with the bunch making mechanism of this apparatus, in which event the latter mechanism merely acts either as a transferring 90 and delivering or bunch manipulating mechanism. The bunch making mechanism of this invention dispenses with the necessity of the employment of cups or molds, intermediate conveying mechanism for transferring the bunch from the bunch making to the wrapper applying mechanism, and also obviates the necessity of trimming the bunch just before it has the wrapper applied thereto, the trimming operation being performed 100 by the bunch making mechanism. When a complete bunch is deposited in the bunch making mechanism by hand, if it is desired to so utilize the bunch making mechanism, the latter then serves solely as a bunch manipulating mechanism.

The machine also embodies a wrapper feeding means, wrapper feeder or wrapper feeding mechanism preferably having suction means coöoperating therewith and auto- 110

matically cutting off the suction from the wrapper in parts proportionate to the amount of the wrapper being wound around the bunch. The wrapper feeding means or device is provided with coöperating mechanism to automatically change the feeding angle thereof relatively to the bunch and also for tilting the same to cause the wrapper to be fed proportionately to the decreasing diameters of the bunch toward opposite extremities of the latter, and, furthermore, the wrapper feeding means or device is given a depressing movement at the tuck end of the bunch. The wrapper feeding means or device also has an actuator and controller coöperating therewith to cause the same to feed the wrapper to a bunch at a speed proportionate and corresponding to the different diameters of the bunch or bunches and at the same surface speed with which the bunch revolves.

In the accompanying drawings, a preferred embodiment of the invention is illustrated, together with modifications of parts thereof, it being understood that the elements therein exhibited may be varied or changed within the purview of the invention, and to render the several parts readily understood and discernible, like reference characters have been applied to similar structures.

In the drawings:—Figure 1 is a view in plan of the wrapper-cutting and wrapper-transferring portion of the machine. Fig. 1^a is a similar view exhibiting the bunch-making mechanism, wrapper-applying mechanism, and wrapper-feeding mechanism. Fig. 2 is a view in side elevation showing more particularly the means for actuating the bunch-making mechanism and for effecting its vibration over the wrapper-applying mechanism. Fig. 3 is a view in side elevation, partly in section, showing more particularly the construction of the wrapper-cutting mechanism. Fig. 4 is a view in sectional elevation of the wrapper-feeding mechanism. Fig. 5 is an end view, partly in section, exhibiting the mechanism for imparting a transverse tilting motion to the feeder mechanism. Fig. 6 is a view in plan showing the mechanism for imparting horizontal arcuate and longitudinal reciprocatory movements to the wrapper feeder mechanism. Fig. 7 is a view in front elevation showing more particularly the mechanism for effecting adjustment of the wrapper-cutting die. Fig. 8 is a detail view of the mechanism for adjusting the wrapper-cutting rollers. Fig. 9 is a detail view of a portion of the wrapper-feeder mechanism. Figs. 10, 11, 12, 13 and 14 are detail views partly in section, of the heading mechanism and wrapper nicking mechanism. Fig. 15 is a detail view of the paste receptacle. Fig. 16 is a diagrammatic view exhibiting the

manner in which the wrapper is cut or slit by the nicking mechanism. Figs. 17 and 18 are detail views of the wrapper-applying rolls, Fig. 17 showing the same closed around a bunch and applying the wrapper thereto, and Fig. 18 showing the same open to permit discharge of a finished cigar. Figs. 19 and 20 are detail views of the bunch-making rolls, Fig. 19 showing the same closed around a bunch and applying the binder thereto, and Fig. 20 showing the same open to discharge the bunch into the wrapper-applying mechanism. Fig. 21 is a detail perspective view of the bunch cutter or trimmer. Fig. 22 is a detail perspective view of the temporary binder and filler or bunch supporter. Fig. 23 is a perspective detail view of the plunger for forcing the bunch or filler, together with the binder and filler or bunch supporter down between the bunch-making rolls. Fig. 24 is a sectional detail view in elevation of the mechanism for opening and closing the bunch-making rolls. Fig. 25 is a sectional detail view in plan of the mechanism for opening and closing the bunch-making rolls. Fig. 26 is a perspective view of the grippers and tuck-cutting mechanism. Fig. 27 is a sectional detail view of the tucking mechanism. Figs. 28, 29 and 30 are detail views of a modified form of nicking and header mechanism. Fig. 31 is a sectional elevation of the mechanism for imparting movement to the carrier. Fig. 31^a is a detail view in diagram illustrating the bunch forming and shaping or manipulating rolls in section and the operation of the binder and filler apron in connection therewith. Fig. 32 is a view in elevation of a modified form of the sector shown in Fig. 2, and Fig. 33 is a sectional view of the modified form of sector shown in Fig. 32, the section being taken on the line 33—33 of Fig. 32.

In describing the mechanism of this apparatus the construction and manner of assemblage of the elements for effecting the results designed, will be divided into sections under headings indicating the parts of the machine to be described, and afterward a full and explicit explanation of the successive steps leading up to the final result will be given.

The order in which the mechanisms will be described, is as follows:—1, Bunch making and transferring mechanism; 2, bunch cutting mechanism; 3, wrapper applying mechanism; 4, wrapper-cutting and transferring mechanism; 5, wrapper-feeder mechanism; 6, wrapper-feeder actuating mechanism; 7, wrapper-tucking mechanism; and 8, tuck and cutting mechanism.

Before describing the invention it is desired to point out tersely one of the salient and all important features of this invention, and that which differentiates it from the

art to which this invention relates, and that is the employment of a bunch-making mechanism embodying a plurality of rolls, said mechanism constituting at once a bunch maker and a bunch transerrer. Heretofore, several mechanisms have been employed to effect the result accomplished by the single aggroupment of elements of this invention, for effecting the formation of the bunch, the application of the binder thereto, and the transferring of the bunch from the bunch-making mechanism to the wrapper-applying mechanism. By making one combination of elements perform the series of functions described, the employment of a bunch-making table, a bunch-transerrer, in the nature of an endless conveyer or of swinging arms, and means for depositing the bunch within the wrapper-applying mechanism, is obviated. It will be apparent that by eliminating such a number of parts, which are of somewhat intricate nature, not only will the operation of the machine be simplified, but its cost of production will be correspondingly reduced and danger of derangement and breakage of parts will be minimized.

Bunch making and transferring mechanism.—The bunch-making and transferring mechanism comprises a plurality of yielding rolls 1, of which there may be any desired number. As shown in Figs. 19 and 20, the rolls are divided in two series of three each and are carried by two pairs of jaws 2 and 3 adapted to open and close to receive and discharge a bunch, as will presently appear. Motion is imparted to the rolls through the medium of a pinion 4 with which the pinions 5 of the rolls are adapted to mesh when in closed position, as clearly shown in Fig. 1^a. The shaft of the pinion 4 carries a motion transmitting gear-wheel 6, with which meshes a gear 7 carried by the inner end of a stub-shaft 8 suitably journaled in the side frame 9 of the machine, the outer end of said shaft 8 having keyed or otherwise secured to it a gear 10 which meshes with a gear 11 also mounted upon a stub-shaft carried by the side frame 9. It will be seen that when motion is imparted to the gear 11, this will be transferred through the gears 10 and 7 to the gear 6, thus to the pinion 4 and from this to the gears of the various rolls, imparting thereto rotary motion in the desired direction. When the rolls are open, they will remain stationary, but as soon as closed after having received a bunch they will immediately begin to rotate, thus to effect either shaping or compressing of a filler or a bunch, or the shaping of a bunch or the wrapping thereon of a binder.

The mechanism for imparting timed or interval rotary motion to the gear 6 comprises an internally toothed sector 12

clearly shown in Fig. 2, the said sector cooperating with a shaft 13 journaled in a slide 14, clearly shown in Fig. 24, said slide having a dove-tailed connection with a guide 15. The sector has rigidly connected with it a cone 16, shown in detail in Fig. 24, the base of the cone constituting the slide, and to this base is secured a downward extending stud or projection 17 which works in a slot 18 in the guide, and said projection is engaged by the forked end of a lever 19 fulcrumed intermediate of its ends upon a bracket 20 secured to a fixed part of the machine (Fig. 24), the lower end of the lever being provided with a roller bearing 21, which engages a cam groove 22 in a cam 23 mounted upon the main drive shaft 24. When the cam 23 revolves, and the roller passes to the proper portion in the groove thereof to shift the lever 19, the slide and with it the sector are thrown laterally, thereby bringing the sector over the gear 6 and into position to mesh therewith. When the sector is shifted, the cone 16 rides against a ball or anti-friction bearing 25 carried by a slide 26 mounted for sliding movement upon a guide 27 carried by an arm 28^a mounted at one end upon the shaft 13 and carrying at its opposite end the pair of jaws 2, a pair of jaws 3 being carried by a similar arm 29 also mounted upon the shaft 13, as clearly shown in Fig. 1^a. A spring 28 is provided, one end of which bears upon the end wall of the guide 27, and its opposite end against an extension 31 of the slide (Fig. 25) said spring operating normally to hold the bearing 25 against the cone. The slide has connected with its outer end a cross piece 32 having connected at each end thereof one end of a pair of rods 33 and 34, the opposite ends of which are connected, respectively, to the jaws 2, as clearly shown in Figs. 19 and 20.

As will be seen in reference to Fig. 19 the rod 33 is connected with one jaw above its pivotal point and the rod 34 with the other jaw below its pivotal point, and it will be seen from this arrangement that when the slide is forced rearward through the movement of the cone 16, the jaws will be closed around a bunch and be held in this position until the rolls are brought into position to discharge the bunch, whereupon the cam 23 will operate to shift the lever 19 in the opposite direction, thus to move the cone back to its normal position and permit the spring 28 automatically to effect opening of the jaws and thus the release of the bunch. At the same time that the slide 26 is actuated to close the jaws, rotary movement is imparted to the two arms 28^a and 29 supporting the rolls through the medium of a sector 35, clearly shown in Fig. 1^a in full lines, and in dotted lines in Fig. 2, this sector meshing with a gear 36 mounted upon the 130

shaft 13 and fast to the hub portions of the arms 28^a and 29. The sector 35 is fulcrumed to a rock-shaft journaled in suitable bearings in the frame, and near one end of the shaft and in alinement with the shank of the sector is secured an arm 38, the free end of which carries a roller 39 working in a cam groove 40 cut in the face of a wheel 41 mounted upon the shaft 24, the cam groove being shown in Fig. 2 and the wheel in Fig. 1^a. The throw of the cam is so timed that when the rolls close, the sector 35 is rocked, thereby lifting the arms 28^a and 29, and with them the rolls, bringing the gear 6 into mesh with the teeth of the sector 12. As the arms continue to move the rolls are driven and the bunch therein is rolled, compressed and shaped and is transferred to a point of discharge, where the bunch may be delivered, for example, to wrapper-applying mechanism; and when this point is reached the cone 16 and the sector 12 are again moved laterally, thereby opening the rolls and throwing the sector 12 out of engagement with the gear 6, whereupon rotation of the rolls ceases. By shifting the sector 12 laterally, it will be thrown out of the path of the gear 6, so that upon the return movement of the arms 28^a and 29, the rolls will remain open and thus in position to receive a fresh bunch.

Coacting with the bunch-making rolls is a binder and filler or bunch supporter comprising a flexible apron 42 held by an arm 43 arranged over but to one side of the rolls, thus to be out of the path of the movement thereof. The arm 43 is carried by a vertical slide bar 44, the lower end of which connects with one end of a lever 45 fulcrumed at 46 to a fixed part of the machine and having at its free end a roller 47 to engage a cam groove 48 in the wheel 41, the operation of the binder and filler or bunch supporter being such that when the bunch-making rolls are open the said apron will be down and bridge the space between the rolls, the apron being thus positioned as the rolls resume their normal position, and the rolls in such resumption pass under the supporter and cause the same to rest thereon. The apron receives the filler and also supports the inner end of the binder, and to force the filler and binder down in between the rolls, or into the position shown in Fig. 19, there is a plunger 49 provided, shown in detail in Fig. 23, the head 50 of which is of a length equal to the length, or approximately the length, of a bunch, and has its under face concaved or grooved to conform to the shape of the bunch. This plunger has an arm 51 which is connected with a vertical bar 52, (Fig. 2) the lower end of which is pivoted to a lever 53 fulcrumed intermediate of its ends upon a fixed part of the frame of the machine, the inner or free end of the lever having a roller

54 adapted to travel in a cam groove 55 in the face of the wheel 41. The cam groove 55 is of such contour that the plunger is held raised until the filler has been placed upon the supporter and the binder is positioned, whereupon it descends and forces the supporter, together with the filler and binder, down between the rolls forming a pocket therein, and immediately thereafter ascends. By the time it reaches the limit of its upward stroke, the bunch-making rolls are closed by the mechanism before described, thereby compressing the filler and inclosing the free end of the binder within them. Before the rolls start to lift, or to have swinging movement imparted to them, the supporter is thrown out by the rotation of the rolls and is then lifted by the bar 44. It is to be understood, of course, that while the plunger is advantageous for use in connection with the binder and filler or bunch supporter 42, it is not absolutely essential as the operator could place the filler and binder upon the supporter and by hand force them down in between the bunch-making rolls. This supporter may be omitted or removed, if desired, and the bunch disposed directly by manual operation in the bunch-making rolls without the use of mechanism devised for this purpose.

To effect a smooth and regular feed of the binder to the filler, there is provided a tension means or support 56 for a binder, consisting essentially of a box-like structure having a perforated top, the box having suitable suction mechanism combined with it to hold the binder under tension. The binder may be placed by hand upon the tension means and held tightly thereagainst by the suction, and in being drawn therefrom by the movement of the bunch-making rolls is held taut, and smoothly fed to the bunch; but the resistance presented to its withdrawal from the tension means will not be sufficient to cause any tearing.

While the sector 12 herein shown is toothed throughout its length, it will be obvious that if preferred it may be toothed only a portion of its length, thus to reduce the number of revolutions of the rolls and the compressing action thereof, or if preferred, the toothed portions may be made in sections 12' which may be removable for the same purpose as shown in Fig. 32, or for starting or stopping the revolutions of the rolls if found necessary or desirable.

Bunch cutting mechanism.—While the bunch with the binder is being rolled and compressed within the bunch-making rolls, it is longitudinally lengthened and for the presentation of a perfect bunch it is necessary that the protruding portions of the bunch should be removed before the bunch is transferred to the wrapper-applying mechanism. This mechanism comprises a

pair of shears or clippers shown in detail in Fig. 21, and comprising two arms 57 and 58, suitably pivoted together and having their upper ends formed into knives or blades 59, the said arms being supported by a trunnion 60, clearly shown in Fig. 1^a. The arm 58 has a link 61 movably attached thereto, and to the lower end of the arm 57 is movably secured a link 62, the free end of the latter 5 being pivotally connected to an arm 63 carried by a shaft 64. A second arm 65 on shaft 64 is terminally pivoted to the lower end of the link 61. The shaft 64 carries a gear 66, and upon the shaft is mounted a coiled spring 67, one end of which is connected with a pin 68 projecting inward from the side of the machine, and the other end is secured to the shaft 64. The shaft 10 also carries a pin 69 which normally engages a stop 70 projecting inward from the side of the machine, the stop serving to check the rotation of the shaft 64 due to the action of the spring. The gear 66 is actuated by a toothed sector 71 on the wheel 41, 15 the said toothed portion being just sufficient to impart the desired portion of a revolution to the gear 66 to cause the knives 59 to close and sever the protruding part of the bunch and binder. The operating gearing 20 set forth is so timed that the knives operate just as the bunch-making rolls start to be transferred, and immediately thereafter are caused automatically to open through the medium of the spring 67, as it will be seen 25 that when the toothed portion of the wheel 41 passes beyond the gear 66, the spring 67 will then be free to exert its power to revolve the shaft in the direction to cause the knives to open or resume a normal condition. The pin 69, by engagement with the stop 70 serves to check the rotation of the shaft 64 at the proper instant.

Wrapper applying mechanism.—The wrapper-applying mechanism comprises a plurality of rolls constructed in the same, or substantially the same, manner as those of the bunch-forming mechanism, and in this instance, as shown in Figs. 17 and 18, comprises five rollers 71^a, two of which are carried by a pair of arms or jaws 72 and 73, and the three remaining by a pair of arms or jaws 74 and 75. The shank of each of the rollers carries a pinion 76, the series being arranged in staggered order, as shown 45 in Fig. 1^a, to prevent interference, and motion is imparted to the series of pinions through a gear 77 carried by a hollow shaft 78 suitably journaled in a bearing 79 on one side of the frame, and to the shaft is 50 secured a gear-wheel 80, which meshes with a mutilated gear 81 carried by a wheel 82 arranged at the side of the machine, the said mutilated gear operating also to drive the gear 11 which operates, through interposed 55 mechanism, the rolls of the bunch-making

mechanism. The wrapper-applying rolls are adapted to open to receive a bunch from the bunch-making mechanism when the same is brought thereover, and thereafter to close to apply a wrapper, to the bunch, the 70 mutilated gear 81 being so timed in its movement as to effect rotation of the rolls only when the bunch which is to have a wrapper applied thereto is therein.

As shown by Fig. 1^a, the gear 11 is rendered inoperative when the inner mutilated portion of the gear 81 on the cam wheel 82 comes under the same. In other words, during the time that the binder and filler are being inserted in the rolls 1 of the bunch-forming mechanism, the latter is inoperative by reason of the fact that the gear or pinion 11 is over the untoothed portion of the gear 81, but as soon as the said gear or pinion 11 engages the teeth projecting 85 fully across the periphery of the gear 81 the bunch-forming mechanism is operated and continues to operate until it starts to move over toward the wrapper applying mechanism and immediately the teeth of the segment 12 are engaged by the pinion 6, the bunch-forming mechanism is again set in motion to shape or manipulate the bunch, and this movement of the bunch-forming mechanism continues until just prior to the 90 deposit of the bunch within the wrapper applying rolls. During the movement of the bunch-forming mechanism as just described the cam wheel 82 having the gear 81 thereon will be regularly rotated and when 100 the bunch-forming mechanism is returned to normal position the mutilated portion of the gear wheel 81 will be under the gear or pinion 11. The gear or pinion 80 is continuously rotated as it engages the outer 105 portion or continuous line of teeth of the gear 81 and hence the wrapper applying rolls will be continuously operated in view of the fact that the wrapper applying mechanism as a whole must be working while the bunch-forming rolls are returning to normal position and while making successive bunches so that the supply of the bunches 2 and the discharge of the wrapped bunches from the wrapper applying rolls may be carried on in 110 115 regular order.

The means for opening and closing the wrapper-applying rolls and the jaws 72 and 74 consists of a pair of arms 83 and 84, one of which is carried by the jaw 72 and the other by the jaw 74, as clearly shown in Fig. 17. The outer end of each of these arms carries a laterally-projecting roller 85 and 86, respectively, the said rollers engaging cam races 87 and 88 in the face of the wheel 120 82, as shown in Fig. 2. These cam races are so timed that the rollers will remain closed long enough to complete the application of the wrapper to the bunch and the finishing 125 of the tip thereof before they open to permit 130

the finished cigar to be discharged from the said mechanism.

Combined with the wrapper-applying mechanism is a nicker for cutting a slit at the tip end of the wrapper to cause it to fit the tip of the cigar without creasing or wrinkling, and also a cutting device for removing the surplus wrapper after severing by the nicker and for polishing and finishing the tip of the cigar. The nicking mechanism shown in Figs. 10, 11 and 13 comprises a rotary armed knife 89 carried by a shaft 90 which is journaled in a slide block 91 working between guides 92 suitably supported on the upper portion of the frame of the machine. The shaft 90 carries a pinion 93 which meshes with a pinion 94 carried by one end of a shaft 95, the other end of the shaft having secured to it an elongated pinion 96 which meshes with the gear 71 of the wheel 41. The two jaws 72 and 74 each carry the half section of a conical cup 97, constituting as to its exterior the male member of a die, the end of which is open to permit the tip of the cigar to project therethrough to be operated upon by the tip polishing mechanism, presently to be described. The cup members, as clearly shown by Figs. 11 and 13, are spaced apart upon their upper sides to present a gap or slot 98 through which the flap to be severed by the nicking knife can escape, and in operation the face of the nicking knife impinges against the outer end of the cup 97, as clearly shown in Figs. 10 and 11, and thus effects the formation of a slit at the tip end of the wrapper, as shown diagrammatically in Fig. 16, while the wrapper is being wound around the bunch at the head end of the latter, to thus form a flap on the wrapper and permit the bunch to take up the wrapper at its head end without accumulation of superfluous wrapper, the superfluous wrapper material being removed or cut off by means which will also be presently described. It is only essential that the nicking knife should coact with the cup 97 when the tip of the cigar is to be finished, and, to permit the tip-forming mechanism to perform its function and also to allow the cigar to be discharged, the nicking knife is moved laterally away from the cup during these operations. This lateral movement of the nicking knife is effected through the medium of a cam race 99 in the wheel 41, the slide block 91 carrying the shaft 95 being provided with a friction roller 100 to engage the cam race. This race is so constructed that the slide block, and with it the nicker, is brought into operative relation with the cup 97 only at such times as is necessary to nick a wrapper, at other times the said block being moved backward, thus to permit the wrapper applying rolls to freely open and close. In order to allow the nicker to perform its

complete function, the elongated pinion 96 is provided, which will be of such length that as the slide block is reciprocated the said pinion will remain in mesh with the gear 71. It will be observed with reference to Fig. 13 that there is a wide gap left between two of the cutting blades of the nicking knife, and this space is provided to permit proper operation of the wrapper head-cutting and tip-polishing mechanism now to be described.

Formed in the guide 92 is a semi-cylindrical case 101, see Fig. 15, in which is splined for longitudinal movement a sleeve 102, the forward end of which serves as a knife 103^a which coacts with the cup 97 to trim off the surplus portions of the wrapper from the flap formed by the nicking knife in advance of the application of the tip-polishing device.

It will be understood from the finishing mechanism thus far described that the portion of the bunch forced into and extending through the header will be cut off and by degrees a slit will also be formed in the wrapper while the latter is wound around the head end of the bunch and thus form a flap on the wrapper and permit the bunch to take up the wrapper at its head end without accumulation of superfluous wrapper material, and, furthermore, means are provided for discontinuing the slitting operation and for causing the female portion of the wrapper heading die to force the wrapper against the male head and simultaneously, or in one operation, cut off the superfluous wrapper material and obtain the shape of the wrapper requisite for the proper head formation of a cigar.

Splined within the sleeve 102 is a shaft 103, the outer end of which is provided with a cone-shaped depression 104, corresponding to the shape of the tip end of a cigar and within which the same fits, the rotation of the cigar imparted by the wrapper-applying rolls causing the tip to be finished by the walls of the said recess. The knife carrying sleeve 102 is brought into co-operative relation with the cup through the medium of a cam groove 105 in the wheel 41, the said sleeve being provided with a roller-bearing 106 to engage said groove, and like motion is imparted to the tip polisher through the medium of a cam groove 107 in the same wheel, said groove being engaged by a roller-bearing 108 on the shaft of the tip polisher.

The operation of this portion of this apparatus is as follows: After a bunch has had the wrapper applied to it in a manner that will presently be described, the nicker is moved up into co-operative relation with the cup 97 and the slit is formed in the tip end of the wrapper, as shown in Fig. 16. When a proper amount of the wrapper has

- been severed by the nicking mechanism to permit the formation of a perfect tip, the knife 103^a is then projected forward and fitting over the cup 97 serves to trim the flap formed by the nicking mechanism, along a line such as dotted line *e*, Fig. 16, to provide a tip end of proper shape, such as *t* in said figure, after which operation the tip former moves up against the tip of the cigar and finishes the same. In order that the wrapper shall be properly secured around the tip of the cigar, suitable paste must be supplied, and in such quantities as will be requisite for the purpose designed.
- 15 To effect this result a paste cup 109 is provided, see Figs. 1^a, 11 and 15, the lower end of which discharges into a duct 110 which communicates through a flexible connection 111 with a passageway 112 formed in the members of the cup, said duct, as shown dotted in Fig. 13, being curved so as to discharge the paste in front of the flap being wound. The supply of paste is automatically discharged by a piston 113, (Figs. 11 and 15) connected with a slide 114, said slide being a hollow structure forming a guide for the inner end of and housing a spring 115 that bears against an ear 116 on the piston. The rear end of the slide carries a roller bearing 117 which is arranged in the path of movement of a cam projection 118 (Fig. 1^a) arranged on the inner face of the wheel 41. It will be seen from the arrangement disclosed that when the cam surface contacts with the roller 117 the slide will be projected forwardly compressing the spring 115 and at the same time projecting the piston 113 which will force out through the passageway 112 a charge of paste sufficient to effect the proper pasting of the tip end of the cigar, and as soon as the cam surface 118 passes the roller 117, the spring 115 will cause the slide to resume its normal position.
- 45 In Fig. 14 there is shown a slightly modified form of wrapper head-cutting and tip-polishing device. In this form of the embodiment of the invention, in addition to the knife 103^a and the tip finisher 104^a there is provided a hollow rotary brush 119 which is projected in advance of the tip finishing device to force the wrapper around the tip of the bunch before the tip is finished. To effect movement of the brush-bearing element into engagement with the tip portion of the cigar, this latter is provided with a bearing 120 adapted to engage with a suitable cam groove or race in the wheel 41. This latter form of tip-finishing device is highly efficient in use and will result in the production of a cigar having a neatly and smoothly finished tip.
- In the form of device shown in Figs. 29 and 30, the jaws 72 and 74 have each a half cup 121 and 122, through which the tip end of the cigar projects when closed. Coacting with the two cups is a cutter for severing the head end of the wrapper and a nicker. The means for nicking the wrapper comprises a rotary cutter 123 (Fig. 28) which is adapted to be projected by suitable mechanism into engagement with the open ends of the two cup sections 121 and 122 when assembled to form the slit in the wrapper as above described, and after this operation cutting away of the surplus wrapper severed by the nicker is effected by a cutting device embodying a male member 124 and female member 125 carried by arms 126 and 127, respectively. Each of the members of the cutting device is a quarter sphere, and the member 124 is provided with a depression 128 to receive one of the cup members, as clearly shown in Fig. 28, and the other member 125 is provided with an approximately vertically-disposed recess 129 through which the wrapper passes. The member 124 is provided with a knife 130 of a shape to cut the desired head formation on the wrapper, and the member 125 is provided with a recess 131 conforming to the knife against which the same coacts in severing the head of the wrapper. By the employment of the members 124 and 125 different shaped head formations may be formed by changing the contour of the knife, and as this will be readily understood, detailed illustration thereof is deemed unnecessary.
- Wrapper cutting and transferring mechanism.*—The wrapper cutting and transferring mechanism, shown particularly in Figs. 1 and 3, comprises a die 132 which is of a shape to conform to that of the wrapper, said die being supported upon a suitable platform 133, and is adapted for adjustment vertically and horizontally, as shown in Fig. 7, to cause proper coöperation between it and the means for cutting a wrapper placed thereon. Coacting with the die is a wrapper transerrer 134, the same comprising a hollow casing provided with a curved neck 135, which is journaled upon a hollow shaft 136 connecting through a flexible conduit 137 with a suitable suction device, not shown. The free end of the transerrer carries a flat perforated plate 138 which also conforms to the shape of the wrapper and is adapted to fit within the walls of the die, as clearly shown in Figs. 1 and 3. The suction on the plate 138 operates to hold the wrapper firmly thereon while being cut to the proper shape to form a wrapper and also while being transferred to the feeder or presenting mechanism, referred to hereinafter. It is of course essential that during the cutting and transferring operation of the transerrer, suction should be maintained first upon the leaf and then upon the wrapper; and it is also essential that the suction should gradually be released so

110

115

120

125

130

a cord or chain 182, see Fig. 4, the opposite end of which passes through a guide 183 in the feeder standard 184, thence passes around a roller 185 at the outer end of the 5 standard, and thence to the rear of the standard and is connected at 186 with the feeder. It will be seen from the description thus far given, that when the toothed portion of the mutilated gear engages the gear 10 181 motion will be imparted to the shaft 177 in a direction to wind the cord 182 around the wrapper-feeder actuator and controller, thereby imparting an inward movement to the feeder to cause the same to move the superposed wrapper toward the wrapper-applying mechanism, and this motion is continued until the feeder has been moved the required distance to effect complete feeding of the wrapper, whereupon the toothed portion 15 20 25 30 35 40 45 50 55 60 65 of the mutilated gear passes out of engagement with the gear 181, thereby stopping the rotation of the wrapper-feeder actuator and controller. To effect automatic return of the feeder to its position, a spring barrel 187 is provided, which is suitably supported by arms 188 on the under side of the wrapper feeder support, and to the periphery of this barrel is connected one end of a cord or chain 189, the other end of which passes around the roller 185 and around a roller 190 and is secured at 191 to the feeder. As the feeder is being moved forward by the wrapper-feeder actuator and controller, the spring in the barrel 187 is placed under tension. When the gear 181 is released from engagement with the gear 81, the spring exerts tension on the cord 189 and effects automatic return of the feeder to its normal position. The function of the wrapper-actuator and controller is to cause the feed of the wrapper to correspond exactly to the speed of travel of the bunch at its various diameters and to provide for the various laps being made around the bunch, the pitch of the groove of the said controller corresponding to the angles of presentation of the wrapper to the bunch, the longitudinal center of the wrapper being caused to correspond to the center of the groove throughout the entire presentation of the wrapper to the bunch, and the pitch of the groove being such relatively to the angular presentation of the wrapper to the bunch as to cause the proper lap of the wrapper around the bunch and obviate the production of what is termed in the art an "overlapped" or "over-rolled" cigar.

Wrapper feeder actuating mechanism.—

There is combined with the wrapper feeder mechanism means for imparting vertically reciprocatory and horizontally arcuate and longitudinal reciprocatory movements thereto, together with means for tilting the feeder mechanism transversely of its standard at the limit of the arcuate movement to cause

the wrapper to be fed in such manner as to correspond to the decreasing diameter of the cigar toward the tip and to closely fit the latter.

The means for imparting vertically reciprocatory movement to the wrapper-feeder mechanism comprises an arm 192, see Fig. 4, one end of which is journaled upon the drive shaft 24, the opposite end having secured to it the table 193 comprised in the wrapper feeding means or wrapper feeding mechanism. The arm 192 carries a stud 194, see Fig. 2, which is engaged by one end of a bell-crank lever 195, fulcrumed at its bend to the side of the machine frame and having at its opposite end a roller bearing 196 which engages a cam race 197 in the face of the wheel 82. The contour of the cam groove or race 197 is such that when the wrapper is first fed to the bunch the table, and with it the feeder mechanism, will be elevated, but as soon as the wrapper starts to be wrapped around the bunch, the portion of the cam groove 197 is presented that causes the table to be moved downward, bringing the wrapper into intimate contact with the first roll of the wrapping mechanism.

The means for imparting horizontally arcuate and longitudinally reciprocatory movements to the wrapper feeder or presenting mechanism to cause the wrapper to follow the contour of the bunch comprises a slide-plate 198, see Figs. 4 and 6, the same being mounted within a frame comprising two side members 199, an end member 200, and an arm 201 which is fulcrumed at 202 upon the rear portion of the table 193. Upon the table is secured a plate 203 having two longitudinally-disposed slots 204 and 205 therein, the slot 204 having its intermediate portion straight and its two end portions curved in opposite directions, and the slot 205 being straight throughout the greater portion of its length and having one end curved to correspond to the curve in one end of the slot 204. The slot 205 operates through coacting mechanism, which will be presently explained, to cause the feeder mechanism to have a longitudinal movement that will effect a relative movement of the superposed wrapper to conform to the shape of the bunch being wound, and to insure a regular application of the wrapper to the bunch, and the slot 204 operates through coacting mechanism to impart particular horizontal arcuate movements to the feeder mechanism, or the wrapper together with the feeder mechanism is caused to follow the bunch in a longitudinal direction, or travel lengthwise of the bunch, and to assume proper angular positions, particularly at the tuck and tip ends of the bunch. To accomplish these results there is provided a gear 206, which loosely

70

125

130

fits in a circular opening 207 cut entirely through the slide plate 198, the wall of said circular opening operating to guide this gear in its rotary movement, and the gear 5 having teeth formed therein over only a portion of its periphery, as clearly shown by Fig. 5. The gear 206 is also provided with an eccentrically disposed, downwardly projecting stud or roller 208, which engages the slot 204. The upper side of the plate 198 is provided with an approximately semi-circular depression or seat 209, in which is disposed a toothed sector 210, the said depression or seat communicating with 10 the circular opening 207, and the sector being held in mesh with the teeth of the gear 206. The toothed sector 210 does not contact with the plate 203, because the lower wall of the depression or seat 209 is interposed between the said sector and the plate 15 203.

The lower portion of the feeder support or standard 184 is provided with an extension 211, see Fig. 4, through which passes 25 a headed stud 212 on which the sector 210 is mounted, the lower end of the stud being provided with a roller bearing 213 which engages the slot 205. To hold the sector against turning any suitable means may be 30 provided, as a pin or bolt 214, which passes through the extension 211 of the feeder support or standard and into the sector.

The forward end of the frame 199 is provided with an arm 215 carrying a ball 216, 35 and engaging this ball is a rod 217 having a socket at each end, one of which engages the ball 216 and the other the ball 218 of a lever 219, the lower end of which is mounted for pivotal movement upon the base of 40 the frame of the machine, see Figs. 1^a, 2, 4, 6, and 31. Connecting with the lever 219 is one end of a rod 220, the other end of which connects with an arm 221 suitably fulcrumed at one end to the frame, the opposite end of the arm 221 being provided 45 with a roller bearing 222 which engages a cam race 223 in a wheel 224 mounted on the shaft 142. Upon motion being imparted to the wheel 224 the cam groove therein 50 operates to rock the lever 219 and thereby turn the frame upon its fulcrum 202. Upon initial movement of the frame and plate, the stud or roller 208 is forced down a curved portion 225 of the slot 204, thereby 55 imparting rotary movement to the gear 206, which latter, by coaction with the sector 210, swings the feeder standard 184 through an arc corresponding to the curve of the tuck or head end of the cigar, thereby causing 60 the wrapper to be properly applied thereto. The stud then passes into the straight portion of the slot 204 and the feeder standard then moves, together with the wrapper presenting devices co-operating 65 therewith, in a straight line so long as the

stud remains in the straight portion of the slot 204, but as soon as the stud enters the curved portion 226 of said slot, the wrapper feeder or presenting mechanism has an arcuate movement imparted thereto which 70 turns the same to a position to cause the wrapper to assume the proper angle to be applied to the tip end of the cigar, and at the same time the stud 212 enters the curved portion 227 of the slot 205, thereby bodily 75 moving the wrapper feeder toward the bunch and causing the proper application of the wrapper thereto. The stud or roller 213 moving in the slot 205 during the accurate swing of the standard 184, the feeder 80 174 held thereon, the slide plate 198 and side members 199, as an entirety, operate to continually move the slide plate 198 inwardly and to maintain the inner terminal of the said slide plate in a uniform spaced 85 relation with respect to the bunch while the said stud or roller 213 is moving in the longitudinally straight portion of slot 205, and the extremity of the feeder 174 will be correspondingly moved, or in other words 90 the slide plate 198 serves to control the feeder 174 with accuracy and reproduction of movement through the standard 184. During the operation of the stud or roller 213 in the slot 205, the roller 208 of the gear 206 is following in the slot 204, the said gear 206 while in the longitudinally straight portion of said slot 204 operating only to such an extent as not in the least to interfere 95 with the inward movement of the slide plate 100 198, but when the stud or roller 213 reaches the terminal of the curved portion 227 of the slot 205, it will be appreciably rotated as the combined feeding mechanism continues to be swung in an arcuate path by engagement with the segment 210, and such operation of the gear 206 at this time will cause the slide plate 198 to continue to move inwardly and correspondingly actuate the feeder 174 through the standard 184 to dispose 105 the wrapper and the inner extremity of the feeder 174 at a proper angle with respect to the tip end of the bunch.

The curve of the slots 204 and 205 exactly correspond to the curves of the wrapper-feeder actuator and controller, and in determining the shape of the cigar, the curves of these parts have to be considered. If different shaped cigars are desired, a different plate 203 and a different shaped 115 wrapper-feeder actuator and controller 176 would have to be employed. In addition, means are provided for causing the wrapper feeder to be tilted transversely at the limit of its arcuate movement to feed the 120 wrapper to the bunch in conformity with the decreasing diameter of the head end of the latter. This mechanism comprises two intermeshing sectors 228 and 229 pivoted upon the outer side of the feeder standard 125 130

184, as clearly shown in Figs. 4 and 5, the fulcrum of the sector 229 being the guide 183 for the flexible connection between the wrapper-feeder actuator and controller and 5 the wrapper feeder, as shown in Fig. 4.

The frame 230 of the wrapper feeder is furnished near its ends with two semi-circular extensions 231 and 232, see Fig. 9, the same being provided with dovetailed tracks 10 233 and 234, respectively, which engage similar shaped guides 235 and 236, formed in lateral extensions on the side of the frame of the wrapper feeder, as clearly shown in Fig. 1^a. The frame of the wrapper feeder 15 is also provided with a downwardly extending projection 237, see Figs. 4 and 9, the lower end of which is formed into a toothed segment 238 which meshes with teeth formed in the upper end of the sector 229. The sector 228 is provided at its lower 20 end with a stud or projection 239, see Fig. 2, which is arranged in the path of movement of a track 240 carried by the slide plate 198 and is provided at one end with 25 a cam surface 241 with which the stud 239 is adapted to engage. When the wrapper feeder reaches the limit of its arcuate movement in feeding a wrapper to a bunch, the stud 239 rides up the cam surface of the 30 track 240 and thereby imparts rotary movement to the sector 228, this motion being transferred to the sector 229 which in turn rocks the wrapper feeder frame transversely and causes the wrapper to conform exactly 35 to the tip end of the bunch. As shown in Fig. 2, there is but one cam surface on the track 241, but under some conditions it might be necessary, where the tuck end of the cigar is very small, to tilt the wrapper 40 feeder frame transversely of the standard for the latter at the said tuck end, and to effect this result the track will be provided with a second cam surface 242, as shown in Figs. 5 and 6. To restore the wrapper feeder 45 frame back to horizontal position, when the same starts to return to its normal position, a spring 243 is provided, which is secured to the fulcrum projection 244 of the sector 228 and has its free end arranged between a 50 pair of studs 246 carried by the sector. It will be seen that as the sector rocks this spring will be placed under tension that will operate automatically to return the wrapper feeder frame to its normal position when the 55 stud 239 is free to permit such operation.

As will be seen by reference to Figs. 5 and 9, the extension 232 is provided with two opening 246^a through which suction is exerted upon the suction box and thus to the 60 wrapper feeder. The feeder standard 184, as shown in Figs. 2 and 4, is a hollow box-like structure, and communicating with the lower portion of the side thereof is a flexible or bellows-jointed pipe 247, (Fig. 1^a) the 65 same being secured at one end to an ex-

tension 248, Fig. 5, on the feeder standard, the opposite end being in communication with the suction device, not shown. By making the pipe 247 flexible, it will yield to the movements of the wrapper-feeding 70 mechanism, thus to permit the suction to be maintained throughout its entire travel.

Wrapper tucking mechanism.—The mechanism for tucking the end of the wrapper around the bunch comprises a needle 249, see Fig. 27, which is secured at its rear end in a slide 250 moving in a rectangular guide 251 supported at one side of the machine, see Fig. 1^a. The needle is flexible and works in a tubular guide 251^a 75 secured to a slide 252 also movable in the guide 251, said tubular guide passing through the shaft 78 hereinbefore described. Each of the slides is provided with a roller 253 and 254, respectively, which engage 80 cam grooves 255 and 256 formed in the periphery of the wheel 82.

Secured to the frame 9 of the machine is an arm 257, at the outer end of which is pivoted an arm 258, the upper or free end of 90 which is provided with a conical opening 259 through which projects the needle 249, and connected intermediate of the length of the arm 258 is a link 260 which is pivotally connected with the outer end of the tubular 95 guide 251^a.

When the wrapper is passing to the bunch, the needle 249 is elevated above the series of rolls 71^a, being held in this position by the arm 258 which is elevated by reason of 100 the fact that the roller 253 engages a part of the cam race 255 to effect this result. When the tuck end of the wrapper is properly positioned with relation to the tuck end of the bunch, the cam race 255 actuates the 105 slide 252 to project it forwardly thereby causing the arm 258 to force the needle down into the rolls, pressing the free end of the wrapper upon the bunch and holding it there until more than a complete revolution 110 of the bunch has been made. Immediately thereafter the cam race 256, by coaction with the roller 254, retracts the needle free from contact with the bunch and holds it in this position until the wrapper has been entirely 115 applied, whereupon the cam race again projects the needle to cause it to enter the center of the cigar to support the tuck end thereof. The wrapper being now applied and having been cut, and the tip finished in the manner 120 described, the wrapper-applying rolls start to open, when suitable gripping mechanism is brought into play to support the tip end of the cigar while the tuck end is being finally severed. The gripping mechanism, 125 as shown in Fig. 26, comprises two semi-circular jaws 261 and 262 carried by arms 263 and 264, respectively, each of the arms being provided with a sleeve 265 and 266, respectively, which are adapted to rotate 130

upon a shaft 267 supported by an arm 268 secured to the frame of the machine, as shown in Fig. 1^a. The sleeve 265 is provided with an arm 269 which is connected to 5 the upper end of a rod 270, and the arm 264 has connected with it intermediate of its ends a link 271 which is pivoted to the rod 270. The lower end of the rod has pivotally connected with it one end of a rock lever 10 272, fulcrumed intermediate of its ends upon a shaft 273 (Fig. 2), the free end of the lever being provided with a roller 274, Fig. 26. On the shaft 267 is also mounted the tuck-cutting mechanism comprising a pair 15 of blades 275 and 276. Rigid with the blade 275 is an arm 277, the free end of which has connected with it a rod 278, the lower end of which is connected with one end of a rock lever 279 fulcrumed intermediate of its ends 20 upon the shaft 273, the other end of the lever being provided with a roller 280, Fig. 26. The rod 278 is connected to one of the blades as 276 by a link 278^a, and as the said rod is moved vertically by its rock lever 279, 25 the link 278^a is similarly moved therewith and both blades 275 and 276 are given a closing movement. The rollers of the two rock levers 272 and 279 are adapted to be engaged by cam projections 281 and 282 on 30 the main drive shaft 24, the projection 281 being designed to actuate the rock lever 272 and the projection 282 to actuate the rock lever 279.

When the wrapper-applying rollers open 35 after the wrapper has been applied and the tip finished, the grippers 261 and 262 are actuated to grip the cigar near its tip end, the tuck end thereof being supported by the tucking needle 249, as before stated. The 40 rolls being now completely open, the rock lever 279 is actuated and the blades 275 and 276 close in upon the tuck end of the cigar and grasp it, but before complete cutting is effected the tucking needle is again actuated 45 to recede from the cigar, whereupon the knives 275 and 276 completely close and sever the tuck end of the cigar. If desired, the grippers 261 and 262 may have suitable branding means associated with them, or 50 label applying or stamping dies may be combined therewith and still be within the scope of the invention. After the knives 275 and 276 have severed the tuck, the rock levers resume their normal positions, thereby opening 55 the grippers and the knives and permitting the finished cigar to drop into a suitable receptacle or to be otherwise removed.

It will be seen from the foregoing description 60 that all of the parts of this machine are constructed with a view to simplicity of construction and certainty of operation, and that by the various actions of the parts, no time is lost in the production of the finished cigar, one operation succeeding the other

sequentially, and resulting in the output of 65 a finished and perfect production.

It is proposed at times to use the bunch making mechanism alone without either the binder-holding and depositing devices or the wrapper-cutting, transferring and applying 70 mechanisms to facilitate the formation of cigar bunches, both manually and mechanically, and under such circumstances the bunches will be delivered to a point where they may be readily removed and have the 75 wrappers applied thereto by hand. In some instances it is also intended to use a series of bunch-making mechanisms duplicates in construction of such mechanism heretofore explained. It will also be obvious that the 80 wrapper cutting, transferring, and applying devices may be used independently, or independent of the bunch making mechanism. To effect this individual operation of the several parts of the machine it will only be 85 necessary to disconnect the intermediate devices controlling the motion of the same from the main driving elements, or in some instances the entire machine may be permitted to operate and only such portions 90 thereof used as may be desired.

Having thus described my invention, what I claim as new, and desire to secure by Letters-Patent, is:—

1. In a cigar machine, wrapper applying mechanism, bunch manipulating mechanism comprising rotating rolls and means for operating them, and means for swinging the said manipulating mechanism to directly deliver a bunch to the wrapper applying mechanism.

2. In a cigar machine, wrapper applying mechanism, swinging bunch-forming mechanism comprising rolls and means for operating them, and means for moving the bunch forming mechanism to deliver a bunch to the wrapper applying mechanism.

3. In a cigar machine, the combination of a bunch manipulating mechanism having a swinging movement, and a wrapping mechanism arranged to receive a worked-up bunch directly from the said manipulating mechanism.

4. In a cigar machine, wrapper applying mechanism, bunch-forming mechanism, and means for moving the bunch-forming mechanism to and over the wrapper applying mechanism and for operating said bunch forming mechanism while moving.

5. In a cigar machine, wrapper applying mechanism, and bunch-forming mechanism having means for overthrowing the same for transferring a bunch bodily into the wrapper applying mechanism.

6. In a cigar machine, the combination of 125 a group of bunch manipulating rolls having a unitedly swinging movement, and a wrapping mechanism arranged to receive a

- worked-up bunch directly from the manipulating rolls.
7. In a cigar machine, bunch manipulating mechanism embodying a series of rolls 5 individually rotatable and all having an over-turning bodily movement, and bunch trimming means coacting with the said rolls.
8. In a cigar machine, an oscillating bunch-forming mechanism having means for 10 rotating the bunch, and bunch-trimming mechanism coacting therewith while the bunch is within the bunch-forming mechanism and while the latter is moving.
9. In a cigar machine, bunch-forming mechanism consisting of a group of rotatable rolls unitedly having an over-turning movement and also opening and closing movements for transferring and releasing a bunch therefrom, the rolls being individually rotated during their movement.
10. In a cigar machine, a bodily overturning bunch-forming mechanism comprising a series of rotatable rolls having opening and closing movements, and means for feeding a 25 binder thereto.
11. In a cigar machine, a bodily overturning bunch-forming mechanism comprising a series of rolls all having opening and closing movements, and means for disposing a 30 binder and filler directly within the rolls.
12. A bunch-making mechanism embodying a group of rotatable rolls having an opening and closing movement and also an over-turning movement, and a temporary 35 binder and filler or bunch supporter coacting therewith and movable into and outwardly from the rolls.
13. In a cigar machine, bunch-forming mechanism embodying a series of rolls, a 40 flexible binder and filler or bunch supporter, and means for moving the supporter into engagement with the rolls, the latter being operated to release the supporter from engagement therewith.
- 45 14. In a cigar machine, bunch-forming mechanism embodying a cluster series of rolls, and a vertically reciprocatory flexible binder and filler or bunch supporter coacting therewith.
- 50 15. In a cigar machine, bunch-forming mechanism in combination with a flexible binder and filler or bunch supporter having its free end movable into and out of operative relation to said mechanism.
- 55 16. In a cigar machine, bunch-forming mechanism embodying a series of rolls, a flexible binder and filler or bunch supporter disposed thereover, and means for moving the free end of the supporter into operative 60 relation to said mechanism.
17. In a cigar machine, bunch-forming mechanism embodying a series of rolls, means for opening and closing the same, a binder and filler or bunch supporter, and
- means for forcing the supporter between the 65 rolls when the same are opened in timed relation to the movement of said rolls.
18. In a cigar machine, bunch-forming mechanism embodying a series of rolls, means for opening and closing the same, a 70 flexible binder and filler or bunch supporter, and means for forcing a portion of the supporter between the rolls when the same are opened.
19. In a cigar machine, bunch-forming 75 mechanism embodying a series of rolls, and means for opening and closing the same, a depending flexible binder and filler or bunch supporter, means for moving the supporter to and from the rolls, and means for depressing 80 a portion of the supporter between the rolls when the latter are opened to form a pocket in the supporter.
20. In a cigar machine, bunch-forming mechanism, a binder and filler or bunch 85 supporter, means disposed over the bunch-forming mechanism for raising and lowering the supporter, and means for forcing a binder and filler with the supporter into the bunch-forming mechanism.
21. In a cigar machine, bunch forming mechanism, a suspended binder and filler or bunch supporter, means for depressing the supporter together with a binder and filler into the said mechanism and also for clearing 90 the supporter from the bunch-forming mechanism, and means for moving the bunch-forming mechanism to transfer the bunch.
22. In a cigar machine, bunch-forming 100 mechanism therefor, a suspended binder and filler or bunch supporter coacting therewith, and means for depressing the supporter and supported bunch within the bunch-forming mechanism.
23. In a cigar machine, a group of bodily 105 oscillatable bunch-making rolls having opening and closing movements, in combination with means for disposing bunch members therein.
24. In a cigar machine, bunch-forming mechanism comprising a cluster of bodily movable rolls, means for individually rotating the rolls and for causing all of the same to have bodily oscillatory and over-turning movements, means for opening the rolls to receive a bunch and for opening the rolls to receive a bunch when in one position and to release a bunch when in another position and for thereafter closing said rolls.
25. In a cigar machine, wrapper applying 110 mechanism, bunch-forming mechanism embodying a series of rolls, means for bodily moving the bunch-making mechanism to the wrapper applying mechanism and at the 115 same time actuating the rolls, and means for returning the bunch-forming mechanism to its normal position.

26. In a cigar machine, wrapper applying mechanism, bunch-forming mechanism embodying a series of rolls, means for bodily transferring the bunch-forming mechanism 5 to the wrapper applying mechanism and at the same time rotating the rolls, and means for returning the bunch-forming mechanism to its normal position and rendering the rolls inactive.
- 10 27. In a cigar making machine, oscillatory bunch-forming mechanism embodying a series of yielding cigar shaped elements, wrapper applying mechanism, mechanism for rotating the said elements during the 15 oscillatory movement of the bunch-forming mechanism, a toothed segment, the said mechanism for rotating the elements engaging with the segment to cause the elements to rotate while being moved toward the 20 wrapper applying mechanism.
28. In a cigar machine, the combination with wrapping mechanism, of bunch-forming mechanism operative to deliver bunches formed thereby to the wrapping mechanism 25 and comprising a series of manipulating rolls having rotative movement and also bodily capable of being over-turned from one position to another, means for opening the rolls to permit deposit within the pocket 30 formed by the rolls of a filler and a portion of a binder, and means for closing the rolls and for driving them to effect the rolling of the binder around the filler to produce a bunch.
- 35 29. In a cigar machine, bunch-forming mechanism embodying a plurality of rolls, and means for moving the rolls in one direction and at the same time rotating them and permitting them to move in the opposite 40 direction without rotation.
30. In a cigar machine, bodily traveling bunch forming mechanism, and means for over-turning the said mechanism to effect the discharge of a bunch and for restoring the 45 parts of the bunch-forming mechanism in operative relation while returning to normal position.
31. In a cigar machine, wrapping mechanism, a swinging bunch manipulating mechanism, movable from a normal bunch receiving 50 position, and means for bodily overturning the bunch manipulating mechanism to effect a discharge of the bunch directly into the wrapping mechanism and for restoring the bunch-manipulating mechanism while returning to its normal position.
32. In a cigar machine, oscillatory bunch manipulating overturning mechanisms swinging from a point of reception of a 55 bunch over to a point of delivery of said bunch and pressing the bunch after its formation during vibratory movement of said mechanism.
33. In a cigar machine, oscillatory bunch manipulating overturning mechanism hav- 65 ing a rolling operation during its vibratory movement and constituting bunch presenting and shaping means.
34. In a cigar machine, oscillatory bunch manipulating overturning mechanism hav- 70 ing a rolling operation during its oscillatory movement and constituting bunch presenting, shaping, and transferring means.
35. In a cigar machine, oscillatory bunch manipulating overturning mechanism oper- 75 ating to exert a pressure on a bunch while the latter is held by said mechanism and during movement of the latter.
36. In a cigar machine, oscillatory bunch manipulating overturning mechanism embodying a group of rolls having a bodily movement to transfer the contents thereof, the rolls pressing the bunch held thereby during oscillatory movement of said mechanism as a whole. 80
37. In a cigar machine, oscillatory bunch-forming overturning mechanism embodying a series of rolls, and an actuating device therefor having its operative surface capable of being increased or diminished to vary 90 the duration of rotation of the rolls and modify the pressure of the bunch.
38. In a cigar machine, oscillatory bunch-forming overturning mechanism embodying a series of rolls, means for bodily transferring and overturning all of the rolls, and means for driving the said rolls while being transferred, said means having an operative face whereby the amount of rotation of the rolls may be increased or decreased. 95
39. In a cigar machine, oscillatory bodily movable bunch-making overturning mechanism embodying a plurality of rolls, and differentiating driving mechanism to effect increase or decrease of the duration of ro- 100 tary movement of the rolls.
40. In a cigar machine, bunch manipulating mechanism comprising a group of rolls, driving mechanism for imparting rotary movement to the rolls, a toothed segment, 110 means for bodily oscillating said manipulating mechanism, and actuating mechanism for said driving mechanism, the driving mechanism being adapted to be shifted out of engagement with its actuating mechanism and into engagement with the segment as the bunch manipulating mechanism starts to oscillate. 115
41. In a cigar machine, bunch-forming mechanism embodying a series of rolls, and removable flexible means for bridging the spaces between the inner portions of the rolls. 120
42. In a cigar machine, the combination with wrapper applying means, of a longitudinally and angularly movable wrapper feeder from which a wrapper is moved independently of any pulling action thereon, 125

- and a wrapper feeder actuator and controller operatively connected thereto for causing the feeder to move and feed a wrapper therefrom to a bunch at a speed proportionate to and corresponding to the various diameters of the bunch, the feeding movement of the wrapper being in consonance with the speed of rotation of the bunch to which it is applied.
- 10 43. In a cigar machine, the combination with wrapper applying means, of a longitudinally and angularly movable wrapper feeder provided with wrapper holding means and from which a wrapper is moved independently of any pulling action thereon, and means for holding the wrapper under yielding tension and for returning the feeder to its normal position after the wrapper has been wholly removed therefrom.
- 15 44. In a cigar machine, the combination with wrapper applying means, of a support, progressive movable wrapper feeding means held thereby, and a wrapper feeder actuator and controller operatively connected with the wrapper feeding means.
- 20 45. In a cigar machine, the combination with wrapper applying means, of a support, a progressively shiftable wrapper feeder held thereby for moving a wrapper fully therefrom, and means for tilting the feeder support and feeder to cause the wrapper moved therefrom to conform to the decreasing diameters of the bunch at its head end.
- 25 46. In a cigar machine, the combination with wrapper applying means, of a support, a progressively shiftable wrapper feeder held thereby for moving a wrapper fully therefrom, means for tilting the feeder transversely of the support, and means for automatically returning the feeder to its normal position.
- 30 47. In a cigar machine, the combination with wrapper applying means, of a support, a longitudinally shifting wrapper feeder held thereby for moving a wrapper therefrom, and means for causing the feeder to occupy an angular position to the support while the wrapper thereon is being moved to the bunch.
- 35 48. In a cigar machine, a support, a wrapper feeder thereon, means for depressing the feeder at the tuck end of a bunch, and means operating to tilt the feeder as the wrapper is traveling thereover and being wound around the head end of the bunch.
- 40 49. In a cigar machine, the combination of a wrapper feeder operating to move a wrapper therefrom, and a wrapper feeder actuator and controller which operates to cause the feed of a wrapper to correspond exactly to the speed of travel of a bunch at its various diameters and to serve as a guide in providing for the various laps of the wrapper being made around the bunch.
- 50 50. In a cigar machine, a wrapper feeder operating to move a wrapper fully therefrom, and a wrapper feeder actuator and controller coacting therewith for effecting the feeding of the wrapper to the bunch in proportions equal to the portion of wrapper taken up by the bunch according to the laps of the wrapper around the bunch.
- 55 51. In a cigar machine, the combination with a wrapper feeder, of an actuator and controller comprising a spirally grooved device, the pitch of the groove of which corresponds to the angles of presentation of the wrapper to the bunch, the longitudinal center of the wrapper being caused to correspond to the center of the groove throughout the entire presentation of the wrapper to the bunch, and the pitch of the groove being such as to serve as a guide in providing for the proper lap of the wrapper around the bunch for the purpose set forth.
- 60 52. In a cigar machine, the combination with a wrapper feeder, of a wrapper feeder actuator and controller comprising a spirally grooved device, the transverse diameters of which, between the base lines of the groove, correspond to the different diameters of the bunch.
- 65 53. As a new article of manufacture, a wrapper feeder actuator and controller comprising a spirally grooved body, the transverse diameters of which between the base lines of the groove correspond to the like diameters of the cigar to be made.
- 70 54. In a cigar machine, a wrapper feeder, an actuator and controller connected therewith and operating to actuate the feeder to feed a wrapper to a bunch at a speed proportionate to the different diameters thereof, and means connected with the feeder to effect its automatic return to normal position after the wrapper feeder actuator and controller has performed its function.
- 75 55. In a cigar machine, a wrapper feeder operating to move a wrapper therefrom, an actuator and controller connected therewith and operating to actuate the feeder to feed the wrapper to a bunch at a speed proportionate to the different diameters thereof, and a spring actuated barrel operatively connected with the wrapper feeder to effect its automatic return to normal position after the wrapper feeder actuator and controller has performed its function.
- 80 56. In a cigar machine, a suction device, a wrapper feeder disposed thereover, means for actuating the feeder to feed a wrapper to a bunch at a speed proportionate to the various diameters thereof, a spring controlled feeder returning mechanism, a roller, and flexible means connecting the feeder and the feeder-returning mechanism and passing around the roller.

57. In a cigar machine, wrapper feeder mechanism, and a wrapper feeder actuator and controller coacting therewith, the latter device being positively driven in one direction and then released from its driving mechanism and automatically returned to its starting position. 65. In a cigar machine, bodily overturning bunch-forming mechanism, wrapper applying mechanism, and an oscillatory element for moving the bunch-forming mechanism with the bunch into co-operative relation over the wrapper applying mechanism. 70
58. In a cigar machine, a wrapper feeder operating to move a wrapper therefrom, a 10 wrapper feeder actuator and controller, and a flexible connection between the said parts, said actuator and controller being so constructed as to cause progressive increase and decrease in the speed of movement of the 15 feeder and also of the wrapper as the wrapper is applied to the bunch. 75
59. In a cigar machine, a wrapper feeder operating to move the wrapper therefrom, a bunch holding means, and means for imparting vertically reciprocatory, horizontally arcuate and longitudinally reciprocatory movements to the feeder relatively to the said holding means. 80
60. In a cigar machine, a wrapper feeder 25 operating to move a wrapper therefrom, a carrier on which the feeder is movable, a bunch holding means, means for imparting vertically reciprocatory, horizontally arcuate and longitudinally reciprocatory movements thereto, and means for tilting the feeding mechanism transversely of its carrier at the limit of the arcuate movement. 85
61. In a cigar machine, wrapper feeding 30 mechanism operating to move a wrapper therefrom, means for imparting vertically reciprocatory, horizontally arcuate and longitudinally reciprocatory movements thereto, and means for tilting the feeding mechanism transversely of its carrier at each limit 90 of its arcuate movement. 95
62. In a cigar machine, wrapper applying 35 mechanism, wrapper feeding mechanism operating to move a wrapper therefrom, a carrier therefor, means for imparting arcuate movement thereto, and means actuated by 40 said movement to impart various angles of presentation of the feeding mechanism to the wrapper applying mechanism. 100
63. In a cigar machine, wrapper applying 45 mechanism, wrapper feeding mechanism, a carrier therefor, means for imparting arcuate movement thereto, means actuated by 50 said movement to impart various angles of presentation of the feeding mechanism to the wrapper applying mechanism, and means for effecting transverse tilting of 55 the feeder at the limit of the arcuate movement of the carrier. 110
64. In a cigar machine, a carrier, a wrapper 60 feeder supported by and movable thereover, means for transversely tilting the feeder with relation to the carrier, and means for preventing separation of the 65 feeder and carrier. 115
65. In a cigar machine, bodily overturning bunch-forming mechanism, wrapper applying mechanism, and an oscillatory element for moving the bunch-forming mechanism with the bunch into co-operative relation over the wrapper applying mechanism. 70
66. In a cigar machine, wrapper applying mechanism, bodily overturning bunch-forming mechanism, oscillatory means for transferring the bunch-forming mechanism to a position over the wrapper applying mechanism, and a bunch supporter coacting with the bunch-forming mechanism and movable out of co-operative relation with the same before the bunch-forming mechanism is transferred. 80
67. In a cigar machine, a flexible tucking needle, and a vertically movable tubular pivotally supported guide through which the needle has longitudinal movement and constituting means for raising and lowering 85 the needle. 90
68. In a cigar machine, header mechanism embodying a hollow male member through which the extreme tip end of a bunch projects, means for rotating the bunch within the said member, means for cutting the head end of the wrapper to the desired shape and co-operating with said member, and tip-polishing means movable into and out of engagement with a portion 95 of the cigar projecting from said male member. 100
69. In a cigar machine, heading mechanism embodying a hollow male member through which the extreme tip of a bunch projects, means for rotating the bunch, a female cutting element operating by impact with the male member, against which the head portion of a wrapper is traveling, to cut away the superfluous tobacco at the head 105 portion and leave in the remaining portion a shape necessary to conform to the head shape of a cigar desired, and tip-polishing means coacting with the male member. 110
70. In a cigar machine comprising wrapper heading mechanism, a movable head-piece constituting the male portion of a wrapper trimming die, the inner portion of which is made to conform to the desired shaped head of a bunch and said head-piece 115 being provided with a slot to permit of the wrapper traveling to the bunch at its head end and at the same time guiding the wrapper, a revolving cutter, means to operate the same for cutting off the portion of 120 a bunch extending through the header and by degrees forming a slit in a wrapper while being wound around a bunch at its head end, thus to form a flap on the wrapper and to permit of the bunch taking up the wrapper 125 at its head end without the accumulation thereat of superfluous wrapper, means for discontinuing the slitting operation, and 130

means for causing the female portion of the wrapper heading die to force the wrapper against the male head and simultaneously therewith in one operation cut off therefrom the superfluous tobacco and make the desired shape in the remaining portion of the head end of the wrapper requisite for the proper head formation of a cigar.

71. In a cigar machine, header mechanism comprising a movable head piece constituting the male portion of a wrapper trimming die and provided with a slit and a paste-receiving orifice, means for cutting off the portion of a bunch extending through the header and forming a slit in the wrapper being wound around a bunch at its head, means for forcing the wrapper while travelling against the male header and simultaneously therewith and in one operation cutting from the wrapper the superfluous tobacco and making the desired shape in the remaining portion of the head end of the wrapper requisite for the proper head formation of a cigar, and tip-polishing means coacting with the male header.

72. In a cigar machine, wrapper applying mechanism, a hollow header coöperating therewith during movement of the bunch in applying the wrapper thereto consisting of half cups having opening and closing movements, and means for clearing the header from the wrapper applying mechanism to permit discharge of a finished cigar and the supply to said mechanism of another bunch.

73. In a cigar machine, wrapper applying mechanism, separable members carried by a portion of the wrapper applying mechanism for producing at the head portion of a wrapper a shape conforming to the shape of the head of the cigar to be made, and means for clearing from the head end of the wrapped bunch the portions of the wrapper that have accumulated thereat.

74. A cigar machine embodying the following mechanisms operating sequentially and in the order named; bunch-forming mechanism constituting bunch-compressing, shaping, transferring and delivering mechanism, wrapper applying mechanism, wrapper-cutting and transferring mechanism, wrapper-feeder mechanism, wrapper-tucking mechanism, means for causing the wrapper feeder to present a wrapper at the proper angles with relation to the wrapper applying mechanism and for feeding the same at the proper rates of speed in conform-

ity with the rate of speed of the various diameters of the bunch, head finishing mechanism coacting with the wrapper applying mechanism, and mechanism for severing the 60 cigar at its tuck end.

75. In a cigar machine, a flexible binder and filler or bunch supporter, bunch-forming mechanism, and means for depressing the supporter within the bunch-forming 65 mechanism thereby to form a pocket, the supporter being removed at intervals from the bunch-forming mechanism.

76. In a cigar machine, the combination with a bunch wrapping means, of means 70 for presenting a wrapper thereto at variable angles and speed of delivery, the wrapper presenting means being held by a movable support and having a wrapper feeder with a movement independent of the movement of 75 said support to fully project a wrapper therefrom.

77. In a cigar machine, the combination of wrapper applying mechanism, means for presenting a wrapper thereto, a wrapper 80 transerrer for disposing a wrapper on said means, and an independently operative element controlling the wrapper presenting means for regulating the taut condition of the wrapper fed from the latter.

78. In a cigar machine, wrapper applying mechanism, means for feeding and properly positioning a wrapper with respect to the wrapper applying mechanism, and a wrapper transerrer for automatically placing a 90 wrapper on said feeding means.

79. In a cigar machine, wrapper applying mechanism, movable supporting means, wrapper feeder means movable on the supporting means and having an operation independently of the latter and automatically 95 operative to assume different positions, and controlling means coöperating with the feeder means.

80. In a cigar machine, bunch-forming 100 mechanism embodying a series of rolls, and removable flexible means for forming a continuous contact surface or wall within the rolls.

In testimony whereof I have hereunto set 105 my hand in presence of two subscribing witnesses.

JOSEPH D. LACROIX.
